CRYSTAL HOLDER

Earl F. Kiernan, San Diego, Calif.

Application February 24, 1949, Serial No. 78,203

6 Claims. (Cl. 171—327)

(Granted under the act of March 3, 1883, as
amended April 30, 1928; 370 O. G. 757)**1**

This invention relates to crystal assemblies and, more particularly, to such assemblies wherein the crystal forms a part of the holder or casing, with one surface of the crystal exposed for contact by the external medium surrounding the assembly.

It is an object of this invention to provide a crystal assembly in which a maximum area of the crystal is employed to transfer energy between the electrodes on each face of the crystal and the ambient medium adjacent the crystal holder.

It is another object of this invention to increase the power transfer capacity of a crystal holder assembly.

It is a further object of this invention to provide a sonic transducer in which a large portion of the crystal face is directly in contact with the sonic transmitting medium.

It is another object of this invention to provide insulating means of increased effectiveness at the edge of a transducer crystal, thereby to prevent electrical breakdown around the edge of the crystal between two electrodes mounted on the respective faces of the crystal.

Other objects and many of the attendant advantages of this invention will be readily appreciated as the same becomes better understood by reference to the following description.

In accordance with the instant invention, the crystal assembly comprises a casing, at least one face of which is open. Across this opening and sealed to the edge thereof is mounted a plate-like crystal, which serves to close the opening and to seal the casing. Thin, conducting, plate-like electrodes are mounted, one on each face of the crystal.

When used to transfer energy from an electrical state to a physical or sonic state, it is often requisite that the electrodes have applied thereto a considerable potential. A major problem is thus one of insulating the two electrodes from each other so that the potential does not form an arc around the edge of the crystal between the edges of the two electrodes. To guard against this difficulty, there is provided, in accordance with the instant invention, a sealed chamber which is bordered, at least in part, by an annulus adjacent the edge of the electrode on the inner face of the crystal, this annulus lying across the breakdown path between the two electrodes, so that by providing the chamber with a medium of good insulating properties, the breakdown resistance across the annular path may be made high, thereby preventing electrical breakdown between

2

the electrodes. This insulation may be effected by contacting the annular face around the crystal with an insulating fluid such as oil, or by providing a vacuum adjacent the face, either of which expedites results in high breakdown resistance across the annulus.

A pair of conductors are provided in contact with each of the respective electrodes, and terminate in appropriate terminals to which a suitable electric circuit may be attached.

Two specific embodiments of the invention described generally above will now be illustrated in connection with the accompanying drawings, wherein:

15 Fig. 1 is a perspective, partially sectioned view of a first embodiment of the instant invention; and

Fig. 2 is a similar view of a second embodiment of the instant invention.

20 Referring to Fig. 1, the crystal assembly is shown comprised of a pair of cylinders 11 and 12, made of insulating material and disposed one within the other, thereby forming between them an annular chamber 13. A round, disk-like crystal 14 is mounted across the bottom end 16 of the inner cylinder 11 and sealed to the bottom edge of the cylinder. The crystal 14 is an X-cut, quartz crystal which vibrates longitudinally, that is, in its thickness, so that when an electric field is applied across the thickness of the crystal, a corresponding physical vibration occurs also across the thickness of the crystal.

As shown in Fig. 1, the diameter of the crystal 14 is slightly larger than that of the inner cylinder 11, so that the periphery of the crystal 14 extends slightly beyond the edge of the inner cylinder and terminates in an edge 17. An annular wall 18 is mounted across the bottom edge of the outer cylinder 12 and is provided with a circular groove 19, into which fits the bottom edge of the cylinder 12, thereby simplifying sealing of the edge of the cylinder 12 to the annular wall 18. The inner edge 21 of the annular wall 18 is sealed to the edge 17 of the crystal 14, thereby sealing the bottom end of the annular chamber 13. The annular wall 18 is of greater diameter than is the outer cylinder 12, so that it continues beyond the edge of the outer cylinder 12 and forms a circumferential flange 22 therearound.

50 Another wall 23 is provided at the upper end of the two cylinders 11 and 12, and is made in the form of a cap having internal threads 24 so that it may be screwed onto corresponding thread 26 on the upper end of the outer cylinder 12, thereby to close the upper end of the crystal assembly. A

disk-like washer 27 is positioned between the wall or cap 23 and the upper edges of the cylinders 11 and 12, so that as the cap 23 is screwed on tightly, these edges are sealed to the cap, thereby sealing the upper end of the annular chamber 13, which is filled with a suitable insulating medium such as oil 28.

A pair of thin, plate-like electrodes 31 and 32 are mounted one against each face of the crystal 14. These electrodes preferably consist of thin films of silver and copper evaporated or sputtered onto the two faces of the crystal 14. A terminal 33 is mounted in the flange 22 of the wall 18, and a resilient conductor 34 is secured at one end to the terminal 33, the inner end 36 of the conductor being pressed against the outer electrode 32 to make good electrical contact therewith. Another terminal 37 is mounted in and extends thru the upper wall 23. A conductor 38 extends between the terminal 37 and the electrode 31 on the inner face of the crystal; the inner, resilient end 39 of this conductor also making electrical contact by pressing against the electrode.

Typical use of the assembly illustrated in Fig. 1 is for the purpose of transducing electrical vibrations applied to the terminals 33 and 37 into sonic vibrations emanating from thickness vibrations of the crystal 14. In many cases, to achieve satisfactory transmission, it is necessary to apply high potential difference between the two electrodes 31 and 32. A major problem encountered with the use of such potentials is the danger of voltage breakdown between the edges of the electrodes 31 and 32 around the edge 17 of the crystal 14. This danger is obviated in the instant invention by providing that a closed annulus 41 at the edge of the crystal 14 is in contact with the oil 28 in the chamber 13, the oil constituting a good insulator to prevent arcing around the edge of the crystal. Substantially the same insulating results could be achieved by eliminating the inner cylinder 11, and filling the entire space back of the crystal 14 with oil. This would carry the disadvantage of robbing the crystal assembly of much of its transduced sonic energy, which would be absorbed by the oil contacting the inner face of the crystal 14. By removing the oil from the center portion of the crystal, and allowing the oil to fill only a small annulus at the edge, the power transmitted is substantially doubled, since virtually all of the power is then able to be delivered to the outer face of the crystal 14.

Another embodiment of the instant invention, shown in Fig. 2, comprises a hollow casing 51 of insulating material and having an opening 52 in the lower face thereof. A plate crystal 53 is mounted across the opening, the edge of the crystal 53 being sealed to the edge of an inwardly extending flange 54, forming the border of the opening 52. A thin electrode 56 is mounted against the inner face of the crystal 53, the edge 57 of the electrode 56 terminating short of the opening 52 in the casing 51, thereby leaving an annulus 58 of bare crystal exposed to the interior of the casing 51. An outer electrode 59 is mounted against the outer face of the crystal 53. A resilient conductor 60 extends between the outer electrode 59 and an exterior terminal 61 mounted to the casing 51. A terminal 62 penetrates the upper wall of the casing 51, the penetration of the wall being sealed as shown at 63 around the terminal 62. A resilient conductor 64 extends between the inner end of the terminal 62 and the electrode 56 on the inner face of the crystal 53.

The entire casing 51 is evacuated so that an

annulus of insulation at 58 is provided between the two electrodes 56 and 59, thereby preventing arcing between the two electrodes around the edge of the crystal 53, in a manner similar to that described in connection with the first embodiment.

For the sake of clarity, the crystal and electrodes illustrated in the drawing have been shown considerably thicker than they are in actual practice. It is to be understood that these elements, particularly the electrodes, are actually much thinner than shown.

Obviously, many modifications and variations of the present invention are possible in the light of the above teachings. It is, therefore, to be understood that within the scope of the appended claims the invention may be practiced otherwise than as specifically described.

The invention described herein may be manufactured and used by or for the Government of the United States of America for governmental purposes without the payment of any royalties thereon or therefor.

What is claimed is:

1. A crystal assembly comprising a pair of cylinders, one within the other, forming an annular chamber between, a plate crystal mounted across one end of the inner cylinder and sealed to the edge thereof, the periphery of said crystal extending slightly beyond the edge of said inner cylinder, an annular wall sealed to the edge of said outer cylinder and to the edge of said crystal thereby to seal said chamber at said one end, said annular wall continuing beyond the edge of said outer cylinder to form a circumferential flange, a wall at the other end of said assembly sealed to the cylinder edges to seal said chamber, an insulating fluid filling said chamber, a pair of thin, plate-like electrodes mounted one against each face of said crystal, a first terminal mounted to said flange, a conductor extending between said first terminal and the electrode on the outer face of said crystal, a second terminal mounted to said second named wall, and a conductor extending between said second terminal and the electrode on the inner face of said crystal.

2. A crystal assembly comprising a pair of cylinders, one within the other, forming an annular chamber between, a plate crystal mounted across one end of the inner cylinder and sealed to the edge thereof, an annular wall sealed to the edge of said outer cylinder and to the edge of said crystal and sealing said chamber at said one end, said annular wall continuing beyond the edge of said outer cylinder to form a circumferential flange, a wall at the other end of said assembly sealed to the cylinder edges to seal said chamber, an insulating fluid filling said chamber, a pair of thin, plate-like electrodes mounted one against each face of said crystal, a first terminal mounted to said flange, a conductor extending between said first terminal and the electrode on the outer face of said crystal, a second terminal mounted to said second named wall, and a conductor extending between said second terminal and the electrode on the inner face of said crystal.

3. A crystal assembly comprising a pair of cylinders, one within the other, forming an annular chamber between, a plate crystal mounted across one end of the inner cylinder and sealed to the edge thereof, the periphery of said crystal extending slightly beyond the edge of said inner cylinder, an annular wall sealed to the edge of said outer cylinder and to the edge of said crystal thereby to seal said chamber at said one end, a wall at the other end of said assembly sealed

to the cylinder edges to seal said chamber, an insulating fluid in said chamber, and a pair of thin, plate-like electrodes mounted one against each face of said crystal.

4. A crystal assembly comprising a pair of cylinders, one within the other, forming an annular chamber between, a plate crystal mounted across one end of the inner cylinder and sealed to the edge thereof, an annular wall sealed to the edge of said outer cylinder and sealing said chamber at said one end, a wall at the other end of said assembly sealed to the cylinder edges to seal said chamber, said chamber being occupied by an insulating medium, and a pair of thin plate-like electrodes mounted one against each face of said crystal.

5. A crystal assembly comprising a hollow casing having an opening in a face thereof, a plate crystal mounted across the opening and sealed to the edge thereof, a thin electrode mounted against the inner face of said crystal, the edge of said electrode terminating short of the opening in said casing thereby leaving an annulus of bare crystal exposed to the interior of the casing, the interior of said casing being evacuated to increase the arcing resistance across said annulus, a conductor in contact with said electrode, extending thru the evacuated interior of said casing, and penetrating the casing wall, the penetration of said wall being sealed around said conductor to

maintain the vacuum, another thin electrode mounted against the outer face of said crystal, and a conductor in contact with the other, outer electrode.

6. A crystal assembly comprising a casing having at least one face thereof open, a plate-like crystal mounted to said casing across said open face thereby closing the same, the contacting edges of said crystal and casing being sealed to each other, thin conducting electrodes mounted to both faces of said crystal, a portion of said casing forming a sealed chamber bordered at least by an annulus adjacent the edge of the electrode on the inner face of said crystal, the medium within said chamber being of good insulating properties, whereby to prevent electrical breakdown between said electrodes around the edge of said crystal, and a pair of conductors contacting the electrodes on the respective faces of said crystal.
